RUG DISPLAY DEVICE

Harry L. Rubin, Albert Rubin, and David Rubin,
Long Beach, Calif.

Application February 28, 1949, Serial No. 78,786

4 Claims. (Cl. 40—85)

1

Our invention relates to the field of merchandising displays, and more particularly to a rug display device.

In the conventional retail furniture store it is common practice to place rugs one upon the other, and to display the stacked rugs to prospective customers by the salesman throwing a portion of the uppermost rugs rearwardly on the stack to display the rug situated thereunder. Displaying rugs in this manner has several disadvantages which include: the rugs occupying valuable floor space, the prospective purchaser being able to see only a portion of the rug, and the labor and inconvenience to the salesman in throwing back numerous rugs in order that the customer can see a particular rug which may be situated in the lower portion of the stack. The primary purpose of our invention is to eliminate the disadvantages and inconvenience of the present method of displaying rugs in mercantile establishments.

A major object of our invention is to provide a rug display rack which can be positioned on either the walls or ceiling of a furniture store and thus utilize what is normally waste space, is sufficiently easy to operate as to permit the desired rug to be inspected by a customer either with or without the assistance of a salesman, and is sufficiently attractive in appearance as to add to rather than detract from the decorative motif of the store in which it is situated.

Another object of our invention is to supply a rug display device which has an extremely simple mechanical structure, is capable of being fabricated from standard commercially available materials, does not require the use of skilled personnel in its assembly, and can be sold to the furniture store trade at a sufficiently low price as to encourage its widespread use.

These and other objects and advantages of our invention will become apparent from the following description of a preferred form thereof, and from the drawing illustrating that form in which:

Fig. 1 is a front elevational view of our rug display device;

Fig. 2 is a horizontal sectional view looking upwardly and taken on the line 2—2 of Fig. 1;

Fig. 3 is an end elevational view of the device;

Fig. 4 is a combined elevational and vertical cross-sectional view of the tension control mechanism taken on the line 4—4 of Fig. 1; and,

Fig. 5 is a vertical cross-sectional view of the rug holding girder box taken on the line 5—5 of Fig. 2.

2

Referring now to Fig. 1 for the general arrangement of our invention it will be seen that two laterally spaced hangers H and H' rotatably support a girder box B therebetween, with the box B having a rug R shown in phantom line wrapped therearound. A crank C engages one end of the girder box B rotatable mounting adjacent to the hanger H, and permits torsion to be placed on spring means whereby the weight of the rug R is compensated for when in a downwardly extending position.

The girder box B on which the rug R is wrapped when not being displayed, as may best be seen in Fig. 5, has a rectangular cross-section, and is formed from four longitudinally extending members 10, each of which overlaps and is normal to an adjacent member. The members 10 when thus arranged have a bore 11 of rectangular cross-section extending longitudinally therethrough, with the members being held together by wood screws, cement, or other conventional means normally employed for this purpose.

Situated within the confines of the bore 11 are two laterally spaced wood blocks 12, with each of the blocks having a longitudinally extending bore 13 of annular cross-section formed therein. Each of the blocks 12 is held in the desired position by a number of screws 14 which extend through the members 10 to engage the blocks.

Two rectangular metal caps 15, each having an inwardly extending lip 16 formed around the edge thereof are mounted on the ends of the girder box B. Each of the caps 15 has an inwardly extending boss 17 of rectangular cross-section that engages the outer portion of the bore 11 and at the same time the lips 16 engage the outer surface of the box. A bore 18 of annular cross-section extends longitudinally through each of the caps 15 and bosses 16, and is positioned in co-axial alignment with the bores 13 formed in the blocks 12. Each of the caps 15 has a number of bores formed therein through which wood screws 19 extend to engage the ends of the members 10 and hold the caps 15 in position thereon.

The girder box B is rotatably supported on two shafts 20 and 21, with each of the shafts extending through one of the caps 15 to engage one of the bores 13. The outer portion of the shaft 20 is rotatably supported from the hanger H' while the shaft 21 is similarly supported from the hanger H.

In Fig. 2 it will be seen that the shaft 20 has a helical spring 22 encircling the portion of the shaft situated within the confines of the bore 11. One end of the spring 22 rests against a

washer 23 that is situated against the outer face of one of the blocks 12, while the other end of the spring is held in place by a pin 24 which extends through the shaft 20 adjacent to the inner edge of one of the bosses 17. The helical spring 22 is at all times in compression and tends to move the shaft 20 outwardly. However, the shaft 20 has a ring 25 mounted thereon which is forced against the supporting portion of the hanger H' to prevent appreciable longitudinal movement of the girder box B.

The hanger H' as may best be seen in Figs. 1 and 2 includes a base portion 26 from which a rigid member 27 extends outwardly, with the member 27 having an angularly disposed slot 28 formed therein which rotatably engages the outer portion of the shaft 20 and permits our rug display device to be positioned from either the ceiling or the vertical walls of a showroom. The base 26 has two laterally spaced bores formed therein through which bolts 29 extend to engage the ceiling or wall on which our device is mounted. Due to the spring 22 being at all times in compression, the ring 25 on the shaft 20 is at all times forced outwardly into contact with the inner surface of the member 27, and thus prevents lateral movement of the girder box B for reasons which will hereinafter become apparent.

The hanger H is similar in construction to the hanger H', but is preferably formed with a substantially diamond shaped base 30 having three bores formed therein through which bolts 31 extend to fasten the hanger H to the ceiling or walls of the display room. A rigid member 27 extends downwardly from the base 30 and is provided with an angularly disposed slot 28 therein that rotatably supports the outer end of the shaft 21. Situated on the extremity of the member 27, and on the interior face thereof, is a bolt 33 on which a pawl 34 of conventional design is pivotally mounted. A ratchet 35 is mounted on the shaft 21, and is held in position thereon by a pin 36 which extends through both the ratchet and the shaft.

The ratchet 35 as may best be seen in Fig. 2 is positioned on the shaft 21 adjacent to the interior face of the downwardly extending member 27 on the hanger H. A helical spring 37 is situated in the confines of the bore 11 and encircles the shaft 21, with one end of the spring being affixed to one of the caps 15 by a screw 38 as may best be seen in Fig. 5. The opposite end of the spring 37 terminates adjacent to the outer face of one of the blocks 12, and is rigidly affixed to the shaft 21 by a pin 39 which extends through an eye formed in the spring and a bore in the shaft 21.

The crank C is formed with a handle 40, and a shaft engaging portion 41 of annular cross-section which is adapted to be slidably inserted in the outer end of the tubular shaft 21, with the portion 41 having a slot formed therein which is adapted to engage the pin 36. Thus, by rotating the crank C torsion is placed on the helical spring 37, with the result that the girder box B resists clockwise rotation and thus compensates for the weight of the rug R when it is in the downwardly extending position shown in Fig. 1.

The operation of our invention is extremely simple. The hangers H and H' are mounted on the ceiling or one of the side walls of the display room in the desired position, and laterally spaced from one another at such a distance as to permit the girder box B to be positioned therebetween. The shafts 20 and 21 are each positioned in the

10 hangers H' and H respectively, with the spring 22 at all times being in compression and forcing the girder box B to the left due to the ring 25 engaging the inner surface of the member 27. The desired torsion to compensate for the weight of the rug R when in the downwardly extending displaying position is placed on the spring 37 by rotating the shaft 21 by use of the crank C as previously described. After torsion has been placed on the spring 37 the spring is prevented from unwinding and assuming its initial position due to the pawl 34 engaging the ratchet wheel 35. Of course, when it is desired to remove torsion from the spring 37 the pawl 34 is disengaged from the ratchet wheel 35 which permits the torsion on the spring to rotate the shaft 21.

With the rug R wrapped on the girder box B and torsion on the spring 37, the rug R can be moved downwardly as shown in Fig. 1 by use of a flexible strap 42 that extends downwardly from a rigid bar 43 which is clamped to the lower horizontal edge of the rug. The bar 43 is sufficiently long so that when the rug is moved upwardly due to rotation of the girder box B by torsion on the spring 37, the bar 43 will engage the hangers H and H' and prevent the girder box rotating after the rug R has been fully wound thereon. It will be apparent that if the spring 37 has been adjusted so as to virtually exactly counterbalance and effectively support the rug R in downwardly extended display position, slight upward movement of the suspended portion of the rug R caused by manually lifting the bar 43, the handle 42 or the lower portion of the rug R to a slight extent so as to effectively reduce the weight of the rug supported by the spring 37, will cause said spring 37 to immediately begin to rewind the rug R on the girder box B. Then the rug can be released, and since the effective weight of the depending portion of the rug is now less than it was before, the spring means will exert a greater upward force than the downward force exerted by the weight of the depending portion of the rug R, thus causing the rug R to be entirely rolled up.

While the particular rug display device herein shown and described in detail is fully capable of attaining the objects and providing the advantages hereinbefore stated, it is to be understood that it is merely illustrative of the presently preferred embodiment of our invention, and that we do not mean to limit ourselves to the details of construction or design herein shown other than as defined in the appended claims.

We claim:

1. A rug displaying device which includes: a hollow elongated rug supporting member; block means positioned within the confines of said member, with said means having a longitudinally extending bore formed therein; a pair of plates, with each of said plates being affixed to one of the ends of said member, and each of said plates having a bore formed therein that is in co-axial alignment with the bore formed in said block means; a pair of shafts, with each of said shafts longitudinally positioned in said member and journaled in said bores; a pair of supports, with each of said supports rotatably supporting one of said shafts; spring means situated within the confines of said member and tending to prevent the rotation of said member in one direction; and means to regulate the torsion on said spring whereby the weight of a rug when in a downwardly extending displaying

position is compensated for and said member remains stationary.

2. A rug displaying device which includes: a hollow elongated rug supporting member; a pair of shafts, with each of said shafts journaled in one of the end portions of said member and extending outwardly therefrom; a pair of supports, with each of said supports having an angularly disposed slot that rotatably supports one of said shafts to permit said supports to be positioned on either a horizontal or vertical surface; spring means positioned within the confines of said member, with said spring means tending to prevent the rotation of said member in one direction; crank means for regulating the torsion on said spring means; and ratchet means whereby a rug when extending downwardly from said member in a displaying position will have its weight compensated for and said member will remain stationary.

3. A rug displaying device which includes: a hollow elongated rug supporting member; a pair of shafts, with each of said shafts journaled in one of the end portions of said member and extending outwardly therefrom; a pair of supports, with each of said supports having an angularly disposed slot formed therein that rotatably supports one of said shafts which permits said supports to be positioned on either a horizontal or vertical surface; a ratchet mounted on one of said shafts; a pawl pivotally mounted on one of said supports and engaging said ratchet; a helical spring situated within the confines of said member, with one end of said spring affixed to said member and the other end of said spring to said shaft on which said ratchet is mounted; and a crank which can engage said ratchet bearing shaft, with said crank by being rotated regulating the torsion on said spring, and said ratchet and pawl maintaining said torsion on said spring whereby the weight of a rug extending downwardly from said member is compensated for and said member remains in a stationary position.

4. A rug displaying device which includes: a hollow elongated rug supporting member; a pair of shafts, with each of said shafts having a portion thereof that extends longitudinally into the confines of said member; means for journaling the inwardly positioned ends of said

shafts within the confines of said member; a pair of plates, with each of said plates affixed to one of the ends of said member, and each of said plates having a bore formed therein in which one of said shafts is journaled; a pair of supports, with each of said supports rotatably supporting one of said shafts; a ratchet mounted on the outer end of one of said shafts; a pawl pivotally mounted on a pin extending outwardly from one of said supports, with said pawl engaging said ratchet; a helical spring encircling said ratchet bearing shaft within the confines of said member, with said spring on one end being connected to said member and on the other end to a pin extending through said ratchet bearing shaft; a helical spring situated within the confines of said member and encircling said shaft on which a ratchet is not mounted, with said spring being situated between one side of said journaling means and a pin extending through said shaft, and said spring being at all times in compression; a ring affixed to the outer portion of said non ratchet bearing shaft, with said ring being forced by said compressed spring into the interior surface of one of said supports to prevent lateral movement of said rug supporting member; a crank which can engage said ratchet bearing shaft, with said crank on being rotated regulating the torsion on said spring, and said ratchet and pawl maintaining said torsion on said spring whereby the weight of a rug extending downwardly from said rug supporting member is compensated for; and a horizontally positioned bar affixed to the lower edge of the rug mounted on said rug supporting member, with said bar striking said supports upon said rug being rolled up and preventing further rotation of said member.
